US0D1067731S

(12) **United States Design Patent** (10) Patent No.: **US D1,067,731 S**
 Whitmore et al. (45) Date of Patent: ** Mar. 25, 2025

(54) **TAPERED CUP**(71) Applicant: **BALL CORPORATION**, Westminster, CO (US)(72) Inventors: **Jonathan A. Whitmore**, Denver, CO (US); **Mark A. Jacober**, Arvada, CO (US); **Anthony J. Scott**, Westminster, CO (US)(73) Assignee: **Ball Corporation**, Westminster, CO (US)(**) Term: **15 Years**(21) Appl. No.: **29/855,742**(22) Filed: **Oct. 6, 2022****Related U.S. Application Data**

(62) Division of application No. 29/695,988, filed on Jun. 24, 2019, now Pat. No. Des. 968,893.

(51) **LOC (15) Cl.** ..... **07-01**(52) **U.S. Cl.**USPC ..... **D7/532; D7/509**(58) **Field of Classification Search**USPC D7/396.2, 507, 509-512, 523, 528, D7/532-536, 591, 608
CPC A47G 19/2205; A47G 19/2288; A47G 19/23; A47G 2019/2277; B65D 1/265; B65D 81/3865

CLAIM

The ornamental design for a tapered cup as shown and described.

DESCRIPTION

FIG. 1 is a front perspective view of the tapered cup; FIG. 2 is a front elevation view thereof, the right, left and rear elevation views being substantially the same as the front elevation view;

FIG. 3 is a top plan view thereof;

FIG. 4 is a bottom plan view thereof;

FIG. 5 is a cross-sectional elevation view of the tapered cup;

FIG. 6 is a front perspective view of a tapered cup according to another embodiment;

FIG. 7 is a front elevation view of the tapered cup of FIG. 6, the right, left and rear elevation views being substantially the same as the front elevation view;

FIG. 8 is a top plan view of the tapered cup of FIG. 6;

FIG. 9 is a bottom plan view of the tapered cup of FIG. 6;

FIG. 10 is a cross-sectional elevation view of the tapered cup of FIG. 6;

FIG. 11 is a front perspective view of a tapered cup according to another embodiment;

FIG. 12 is a front elevation view of the tapered cup of FIG. 11, the right, left and rear elevation views being substantially the same as the front elevation view;

FIG. 13 is a top plan view of the tapered cup of FIG. 11;

FIG. 14 is a bottom plan view of the tapered cup of FIG. 11;

FIG. 15 is a cross-sectional elevation view of the tapered cup of FIG. 11;

FIG. 16 is a front perspective view of a tapered cup according to another embodiment;

FIG. 17 is a front elevation view of the tapered cup of FIG. 16, the right, left and rear elevation views being substantially the same as the front elevation view;

FIG. 18 is a top plan view of the tapered cup of FIG. 16;

FIG. 19 is a bottom plan view of the tapered cup of FIG. 16;

FIG. 20 is a cross-sectional elevation view of the tapered cup of FIG. 16;

FIG. 21 is a front perspective view of a tapered cup according to another embodiment;

FIG. 22 is a front elevation view of the tapered cup of FIG. 21, the right, left and rear elevation views being substantially the same as the front elevation view;

FIG. 23 is a top plan view of the tapered cup of FIG. 21;

FIG. 24 is a bottom plan view of the tapered cup of FIG. 21;

FIG. 25 is a cross-sectional elevation view of the tapered cup of FIG. 21;

FIG. 26 is a front perspective view of a tapered cup according to another embodiment;

FIG. 27 is a front elevation view of the tapered cup of FIG. 26, the right, left and rear elevation views being substantially the same as the front elevation view;

FIG. 28 is a top plan view of the tapered cup of FIG. 26;

FIG. 29 is a bottom plan view of the tapered cup of FIG. 26;

and,

FIG. 30 is a cross-sectional elevation view of the tapered cup of FIG. 26.

The dotted lines showing portions of the tapered cup depict environment and form no part of the claimed design.
